UNITED STATES PATENT OFFICE.

PETER E. LASKOWSKI, OF LOS ANGELES, CALIFORNIA.

BAKING-OVEN.

SPECIFICATION forming part of Letters Patent No. 718,260, dated January 13, 1903.

Application filed April 28, 1902. Serial No. 105,125. (No model.)

To all whom it may concern:

Be it known that I, PETER E. LASKOWSKI, a citizen of the United States, residing at Los Angeles, in the county of Los Angeles and 5 State of California, have invented new and useful Improvements in Bakers' Ovens, of which the following is a specification.

My invention has for its objects the production of an oven in which the heat can be 10 perfectly regulated and which can be easily and economically constructed and which can be easily dismantled and removed to another place and set up again. Other objects will be further stated.

15 In the drawings accompanying and forming a part of this specification, Figure 1 is an isometric view of my oven viewed from the front from a slight elevation and at one side of the center thereof. Fig. 2 is a cross-section through the smoke-stack. Fig. 3 is a cross-section through the heat-regulating pipe. Fig. 4 is a longitudinal vertical section a little to one side of the center.

A is the baking-chamber, having a slightly- 25 rounded top composed of two thicknesses of sheet metal B, with an asbestos packing C interposed therebetween, which is strengthened by a longitudinal rib D. The sides and back and front ends of the baking-chamber are 30 composed of two thicknesses of sheet metal, with a packing of sand between. Asbestos packing could be used instead of sand, but I prefer sand, as it is cheaper and holds the heat better. I prefer asbestos for the top, as it is 35 lighter; but sand may be used, if desired.

40 The bottom is formed of a single thickness of sheet metal E, which supports the baking-floor F, composed of some vitreous substance, preferably of red brick. In the front end 45 wall of the baking-chamber is an opening G, the bottom of which slopes downward, and the outer edge lies below the baking-floor, as shown in Fig. 4. This opening is closed by a vertically-movable double door H, which moves in guides I and is opened by a chain or rope J or other suitable means. The purpose in having the opening into the baking-chamber at the front lower than the floor of the baking-chamber is to enable the operator 50 to place material to be baked in the chamber without raising the door the full height of the material being passed therein above the

floor, as he would have to do if the outer edge of the opening were on a level with the floor, the sloping bottom of the opening enabling him to keep the bottom of the door nearer to the plane of the floor of the chamber, and thereby prevent the escape of heat which would otherwise escape if the door were raised the full height of the material 60 above the floor. Should the door not fit perfectly tight at the bottom, less heat will escape through the crack than if such crack were in the same plane as the bottom of chamber. The sheet-metal bottom of the 65 baking-chamber at its outer edges turns downward till it meets the outer bottom wall L. It is supported by three I-beams K, which rest on the outer bottom wall L of the outer casing, which with such casing and the 70 bottom of the chamber form longitudinally-extending draft-flues M and S from the furnaces N and R to the back of the baking-chamber. Furnace N is centrally located and discharges its products of combustion 75 into flues M. This bottom wall is supported by legs O and in the rear of the furnace is of double thickness and is nearer the baking-chamber than it is under the furnaces.

On each side of furnace N, adjacent to the 80 side walls of the outer casing P, are furnaces R, which discharge the products of combustion thereof partly into flues S, formed by the bottom casing of the baking-chamber, the outer I-beams, and the bottom wall of the 85 outer casing, which flues extend to the back of and under the baking-chamber, and partly into the side and top flues T. The front, side, and top walls of the outer casing are 90 double and have a packing of sand U between the two sheets thereof to retain the heat. Running longitudinally on the top of the baking-chamber are I-beams V, which extend to and support the top outer casing and with such casing and the top of the baking-chamber form the top draft-flue W, which extends from the back flue X to front 95 wall of the outer casing. Extending across this top flue, just back of the smoke-stack Y, is a partition-wall Z, which is provided with 100 a number of openings therethrough which are closed by the removable caps a, which are removed therefrom when a hot fire is wanted in the furnaces and are put back when the

smoke from the flue has all practically passed up the smoke-stack and when it is desired to hold the heat around the baking-chamber for slow baking. Access is had to these caps by 5 door *b*, which swings, preferably, inwardly, as shown in Fig. 4. In the I-beams which form the sides of the top flue are openings which are controlled by swinging dampers *c*, having handles *c'*, which extend through the 10 front wall of the oven, so that the openings may be opened to permit the products of combustion from the furnaces *R* which pass into flues *T* to escape therethrough and thence out of the smoke-stack instead of having to 15 travel to the back flue and then pass therethrough and through the top flue and thence out of the smoke-stack.

Leading from the top of the baking-chamber and out through the top wall of the oven 20 is the heat-regulating pipe *d*, the opening through which is controlled by damper *e*, having handle *f* extending to the front of the oven. This regulating-pipe affords convenient means to ventilate the oven and to draw 25 off any steam that may accumulate in the oven or to permit any excess of heat in the oven to escape therefrom. It also affords ready means to clear the oven of the steam used therein in baking those products which 30 require steam in the oven while being baked. A steam-generator *h* is provided to supply steam to the oven when required in baking. A hot-water chamber *i* is connected to the oven to supply hot water when required. 35 The spaces between furnace *N* and furnaces *R* form roasting-chambers *j*, which are provided with doors *k*, through which articles to be roasted are put into and taken out of the roasting-chambers. The casing of my oven 40 is made from sheet metal and is put together with small stove-bolts, so that the several sections may be easily taken apart, thereby rendering it portable. By this construction it will be observed that the heat can be perfectly regulated, as fire may be built in one or 45 more furnaces and may be of different intensity in the different furnaces, and the products of combustion from the side furnaces may be caused to travel the entire length of the baking-chamber and then back to nearly 50 the front thereof at the top, or they can be permitted to pass up the side and over the top, at the front thereof, or to take a similar travel farther back from the front, thus enabling the operator to keep perfect control of the heat in the baking-chamber. A light box or opening *m* is provided to permit the inspection of material being baked. Dampers may be used in the partition of the top flue. 55 Having described my invention, what I claim as new, and desire to secure by Letters Patent, is—

1. An oven comprising a baking-chamber having double top, bottom, back and front 5 walls of sheet metal with a packing therebe-

tween of non-combustible heat-retaining material, and a floor provided with a lining of brick, said chamber having an opening in the front wall, the outer bottom edge of which is below the plane of the baking-floor; a vertically-sliding door adapted to close said opening; a plurality of longitudinally-extending flues beneath said floor; a plurality of furnaces beneath and at the front end of said flues in communication therewith; flues at 75 the sides of said chamber extending partly over the top and to the back of said chamber in communication with the side furnaces; a back flue; a top flue extending longitudinally and centrally over the top of said chamber 80 from the back to the front thereof, said top flue being provided with a perforated partition in the rear of the smoke-stack; caps to cover the perforations in said partition when desired; openings in the side walls of the top 85 flue; dampers to control said openings; and a smoke-stack.

2. In a baker's oven three furnaces in the front thereof under the floor of the baking-chamber; the central furnace being in communication with a plurality of flues extending longitudinally beneath the baking-chamber floor; each of the side furnaces being in communication with a longitudinal flue beneath the baking-chamber floor, and also in 95 communication with side flues, in combination with a baking-chamber provided with flues as described.

3. In a baking-oven, the combination of a baking-chamber; bottom flues extending longitudinally the baking-chamber flues at the sides and over a portion of the top thereof; a back flue; and a longitudinally centrally extending top flue in communication with said bottom and side flues; and a smoke-stack. 105

4. In a baking-oven side flues extending longitudinally the sides of the baking-chamber, a longitudinally-extending flue disposed over the top of the baking-chamber having openings in the sides thereof in communication with said side flues, and dampers to control said openings. 115

5. In a baking-oven a longitudinally-extending flue disposed over the top of the baking-chamber in communication with the 115 smoke-stack; said flue having a partition-wall extending thereacross in the rear of the top, at the front thereof, said partition being provided with a plurality of openings therethrough, removable caps adapted to close the openings 120 in said partition.

In witness that I claim the foregoing I have hereunto subscribed my name this 7th day of April, 1902.

PETER E. LASKOWSKI.
